CLAIM

The ornamental design of a folded paper towel dispenser, as shown and described.

DESCRIPTION

FIG. 1 is a top, front, and right side perspective view of a folded paper towel dispenser showing my new design;

FIG. 2 is a front elevational view thereof;

FIG. 3 is a right side elevational view thereof, the left side being a mirror image of that shown;

FIG. 4 is a rear elevational view thereof;

FIG. 5 is a top plan view thereof; and,

FIG. 6 is a bottom plan view thereof.
